UNITED STATES PATENT OFFICE.

THOMAS DUFFY, OF GRAND ISLAND, NEBRASKA.

VAPORIZER.

Application filed January 28, 1924. Serial No. 689,115.

This invention relates to vaporizers for use in hospitals and the like for discharging medicated vapors into rooms and wards for the treatment of patients.

- 5 The object of the invention is to provide a simple and efficient machine of this character for quickly producing a medicated vapor and discharging it at any desired point.
- 10 With the foregoing and other objects in view which will appear as the description proceeds, the invention resides in the combination and arrangement of parts and in the details of construction hereinafter described
- 15 and claimed, it being understood that changes in the precise embodiment of the invention herein disclosed, may be made within the scope of what is claimed without departing from the spirit of the invention.
- 20 The accompanying drawing represents a vertical section of a vaporizer constructed in accordance with this invention.

In the embodiment illustrated a supporting structure in the form of a stand 1 is shown on which is fixedly mounted a tank 2 which will be termed an inoculator. This tank 2 is closed except at its top and has a drain cock 3 at the bottom thereof with a water gage 4 arranged at the side opposite 30 that having the drain cock. A coiled steam pipe 5 enters the tank 2 through one side wall preferably near the top the lateral extension of which outside the tank is equipped with a valve 7 for controlling the supply of steam through said pipe. This pipe 5 leaves the tank near the bottom thereof and has a lateral extension 8 equipped with a valve 9 for controlling the steam discharged.

A water pipe 10 enters tank 2 near its upper end and is provided with a control valve 11 between which and the tank a branch pipe 12 connects with pipe 10 and is designed for supplying a medical compound and mixing it with the water which enters tank 2 through pipe 10. The branch pipe 12 is supplied with a control valve 13 for regulating the medical compound passing through pipe 12.

A casing 15 is mounted on tank 2 and has an opening 14 in its bottom which communicates with the tank and over which is supported a decomposer 30 presently to be more fully described.

The casing 15 forms a vapor chamber closed except for the opening 14 in the bottom thereof and leading from the top of

which are a plurality of conduits 28 having suction fans 29 mounted therein. This chamber 15 has an air port 16 opening through one end wall and equipped with a control valve 17. A steam pipe 18 divides into two branch pipes 20 and 21 which pass through the casing 15 and are provided with control valves 22 and 23 respectively for regulating the steam entering through said pipes and at their outer ends have similar valves 24 and 25 for controlling the discharge of the steam.

The vapor chamber 15 is provided above the pipes 20 and 21 with a foraminous partition 26 on which is designed to be supported purifying or filtering material forming a purifying chamber 27 into which the vapor filters and passes out through the pipe 28 to the rooms or wards in which the patients are located who are to be treated by these vapors.

The decomposer 30 which is supported over the opening 14 connecting the inoculator with the vapor chamber is supported by legs 31 or other suitable means and is divided by a horizontal partition 32 into upper and lower compartments 33 and 34. A steam pipe 35 is passed through chamber 15 and the decomposer chamber 33 and is equipped outside the chamber 15 with a controlling valve or cock 36.

A pipe 37 enters through one wall of the chamber 15 and discharges into the compartment 34 of the decomposer said pipe supplying the medical compound to be used in the decomposer the quantity being controlled by a valve 38 in said pipe located outside chamber 15.

In the use of this apparatus water is supplied to the inoculator 2 through the pipe 10 the valves 13 and 9 being closed during this operation. After the desired quantity of water has entered the tank the valve 11 is closed and valve 7 opened to permit steam to pass into the coil 5 in the tank. A suitable amount of medical compound is then added to the water in the tank 2 by opening valve 13 after which valve 13 is closed. The top 39 of chamber 15 is then removed

and a purifying compound spread over the perforated tray 26 and the lid or cover replaced and tightly secured. The valve 9 is then opened to permit steam to flow through the coil 5 so that the combined water and medical compound in the tank 2 is heated sufficiently to produce vapor. The valves 24

and 25 are closed and valve 19 opened as well as the valves 22 and 23 which permit steam to flow into pipes 20 and 21 which pipes superheat the vapor in chamber 15 to any desired degree. The superheated vapor then passes through the purifying material in chamber 27 and is sucked by the fans 29 through pipes 28 which conduct the vapor to the rooms and wards in which the patients to be treated are located. It will be readily understood that this superheating of the vapor materially alters its character, and, if carried to a sufficiently high degree, converts it into a dry gas. It will be found that vapor so treated is much more effective than would be the case if the superheating were omitted.

In case quick service is required the inoculator 2 is not used. The steam valve 36 is closed and valve 40 opened permitting steam to flow into decomposer 30. Valve 38 is then opened to admit the medical compound to the decomposer the contents being heated by the steam entering through pipe 35 thus vaporizing the compound. The vapors so produced contact with the steam heated pipes 20 and 21 and are superheated thereby and pass out through chamber 27 and pipes 28 in the manner above described.

It is of course understood that when a large amount of vapor is required the inoculator is brought into use and combined with the decomposer for supplying vapor to the rooms. The decomposer supplies additional medicated vapor which combines in the vapor chamber with that supplied by the inoculator.

I claim:—

1. In an apparatus of the class described, the combination of a tank for water, means for supplying medicinal matter thereto, and a heater for the tank, whereby medicated vapor is formed, a vapor-receiving and superheating chamber communicating with said tank, and means for delivering the superheated vapor from said chamber.

2. In an apparatus of the class described, the combination of a tank for water and a heater for the tank, whereby vapor is formed, a decomposer comprising a heater and means supplying medicinal matter thereto, a superheating chamber into which vapor from said decomposer is delivered, and means delivering the superheated vapor from said chamber.

In testimony that I claim the foregoing as my own, I have hereto affixed my signature.

THOMAS DUFFY.
